UNITED STATES PATENT OFFICE

2,371,616

PRODUCTION OF VALUABLE HYDROCARBONS

Edwin L. Hall, Philadelphia, Pa., assignor to The United Gas Improvement Company, a corporation of Pennsylvania

Application January 27, 1940, Serial No. 315,936

2 Claims. (Cl. 260—671)

The present invention relates to the simultaneous production of manufactured gas and valuable hydrocarbons, and relates more particularly to increasing the yield of certain of said hydrocarbons.

In the usual manufacture of oil gas or carburetted water gas, a step in the process comprises cracking of crude petroleum oil or its less costly portions, such as gas oil and residuum oil, under conditions which yield relatively large quantities of fixed or difficultly condensable gases, such as hydrogen, methane, and ethylene together with other gaseous paraffines and olefines, and relatively small quantities of more readily condensable hydrocarbons comprising tar, drip oil and lower temperature condensates. Broadly stated, the division between the gaseous and other products depends upon the severity of cracking and the severity of condensation.

It has been proposed to modify the usual conditions of cracking temperatures and time of contact and the temperature of condensation to produce and recover smaller proportions of the original oil as gaseous products for distribution as fuel and larger proportions as condensate containing hydrocarbons more valuable for other uses.

Among the hydrocarbons so recoverable are saturated and unsaturated compounds such as benzene, toluene, xylene, naphthalene, anthracene, indene, styrene, methyl styrene, cyclopentadiene, dicyclopentadiene, butadiene, isoprene, piperylene, etc.

The usual condensation in oil gas manufacture down to atmospheric temperature removes from the gas practically all of the xylene, naphthalene, anthracene, indene, styrene, and methyl styrene, a small part of the benzene, and possibly half of the toluene. For the recovery of the remainder of the benzene and toluene and for the recovery of the above mentioned conjugated dienes much lower temperatures of condensation than usually employed in gas manufacture are required.

Among the aromatic hydrocarbons noted above, the alkylated (including alkylated aromatics are in general more valuable than the benzene. This is particularly true of the toluene, xylene and styrene.

An object of the present invention is to provide an improved method of increasing the yield of alkylated aromatic hydrocarbons relative to the yield of benzene.

Other features of the invention reside in the steps, combinations of steps and sequence of

steps, and in the construction, arrangement and combination of parts, all of which together with other features will become more apparent to persons skilled in the art as the specification proceeds and upon reference to the drawings in which:

Figure 1 shows in elevation and partly in section, a three shell gas set chosen for illustration;

Figure 2 shows a flow sheet illustrating the invention; and

Figure 3 is an elevation, partly in section, diagrammatically illustrating apparatus of the continuous or continual type.

Referring more particularly to Figure 1, 1 indicates a generator, 2 a carburetter, 3 a superheater and 4 a wash box.

Generator 1 is illustrated as having a fuel burner 5, an uprun air blast supply 6, and an uprun steam supply 7.

Superheater 3 is shown with a downrun steam supply 8.

Generator 1 is provided at its top with an off-take 9 leading to the top of the carburetter 2, and carburetter 2 is provided at its base with an off-take 10, leading to the base of the superheater 3.

Superheater 3 is shown with a stack valve 11 and a gas off-take 12, the latter leading to wash box 4 through valve 13.

Generator 1 has a gas off-take 14 at its base provided with valve 15. Gas off-take 14 leads to wash box 4.

Wash box 4 is shown with the conventional gas off-take 16.

Any other gas-making equipment employing a run with oil might have been substituted for the purposes of describing the invention.

The operation of the apparatus will be described with an illustrative cycle.

Liquid or gaseous fuel supplied to burner 5 is burned with air supplied at 6.

The resulting hot blast gases pass up through the generator 1, through off-take 9, down through the carburetter 2 and up through superheater 3, raising the temperature of the carburetter and superheater and storing heat therein, and finally escape through stack valve 11 or to a waste heat boiler (not shown) or otherwise.

If desired, secondary air may be introduced at 17 through pipe 18 controlled by valve 19.

The blast is so conducted as to obtain a desired distribution of heat throughout the carburetter and superheater.

After the air blasting operation the set is purged of blast gases by steam admitted at any

convenient point, such as at 7 or at 23, whereupon stack valve 11 is closed, valve 13 is opened and a forward run with oil is made during which steam is preferably supplied, such as at 7 or at 23.

Supplying steam at 7 has the effect of causing the steam to pass up through the generator whereupon it becomes highly superheated before reaching the carburetter, thus relieving the carburetter from the duty of furnishing this preheat.

It will, of course, be understood that a part of the steam may be admitted at 7 and a part at 23, thus making it possible to regulate the temperature of the steam entering the top of carburetter 2, or all of the steam may be admitted at 7 or 23 with any desired degree of preheat. Reference is made to my copending application Serial No. 191,441, filed February 19, 1938.

Although the point of introduction of oil for the forward run may vary in different gas-making equipment, for convenience in description, I have illustrated an oil spray 21 at the top of carburetter 2.

Irrespective of the construction of the inside of the carburetter, which may vary widely in different types of apparatus, it is customary to have a substantial part of this oil come directly into contact with the heated refractory surfaces, whether they include checkerbrick, or other construction or comprise merely the side walls. However, whether coming into contact with the heated refractory surfaces or not this oil is subjected to the temperatures of the carburetter and superheater, and as it is carried down through the carburetter and up through the superheater along with the steam it is cracked into gas, coke, tar, drip oil and other condensates. The coke is usually deposited in the carburetter and superheater and the condensates are usually carried out of the superheater in the vapor phase and are condensed at the wash box and further on in other condensing equipment.

After the forward run, if desired, a back-run might be made as follows. Valve 13 is closed, valve 15 opened and steam is reversed through the set by admitting it at 8, while injecting oil into the top of the superheater 3 through any suitable mechanism illustrated generally at 24. This oil is carried down through superheater 3 and up through carburetter 2 and is cracked into hydrogen and hydrocarbons which pass down through generator 1 with possibly some further pyrolysis and fixing and off through off-take 14 directly to the wash box 4.

The desired hydrocarbons are condensed at the wash box and/or recovered further on in condensing or other recovery equipment, as in the previous run.

To complete the cycle the reverse run with steam is followed by a forward purge with steam.

The above is a description of a cycle in carburetted water gas manufacture chosen for illustration since a carbonaceous fuel bed might be substituted in the generator 1 for burner 5. Any other appropriate cycle might be substituted. For instance, the reverse run might be omitted.

After passing through the off-take 16 the gas usually goes through water cooled condensers to a relief holder and from thence to the purifiers for the removal of hydrogen sulfide, and thence to storage holders for release to the distribution system.

The wash box 4 in which the gas comes in contact with water, and the water cooled condensers

cool the gas down to approximately atmospheric temperature. The tar and oil condensed out in these vessels comprises a residual tar fraction boiling above 300° C., a dead oil fraction boiling between 200° C. and 300° C., and a light oil fraction boiling up to 200° C. and containing practically all of the styrene, indene, and xylene, possibly half or more of the toluene and some of the benzene and other miscellaneous hydrocarbons or "benzol forerunnings." The individual compounds may be recovered from the light oil by fractional distillation.

Usual gas practice does not carry the condensation further. However, if after purification oil gas, for example, is cooled to approximately -65° C., the remainder of the benzene and toluene as well as the dienes, cyclopentadiene, butadiene, isoprene and piperylene, may be condensed out and recovered separately by fractional distillation, leaving the residual gas with hydrocarbons which are for the most part of less than four carbon atoms and which may also be recovered from the gas as will hereinafter appear.

Other condensate recovery means may be combined with or substituted for refrigeration, for example absorption such as in a scrubbing oil, adsorption such as on activated carbon, and/or compression.

By resorting to recovery by stages, these materials may be removed from the gas in more or less concentrated form.

In the normal production of aromatics from the cracking of petroleum oils, the reaction is supposed to proceed generally as follows:

35 Paraffines → olefines and diolefines
→ Cyclic olefines and naphthenes
→ Aromatics

40 Normally, the production of benzene is relatively high compared to the production of toluene and the higher individual aromatic derivatives such as the xylenes, styrene, indene, etc.

45 The production of the alkylated aromatics probably proceeds at least in substantial part by union of benzene with free alkyl radicals as

Benzene + free radicals → alkylated aromatics.

As described and claimed in copending application Serial Number 220,649, filed July 22, 1938 (now Patent Number 2,226,531, dated December 31, 1940), by Newcomb K. Chaney, by increasing the concentration of benzene and lower olefines such as ethylene (but which term also includes propylene) above that caused by the concurrent formation of these materials in the oil cracking operation, the above reaction of benzene with free radicals to form alkylated aromatics is favored.

50 Also the presence of an increased benzene and lower olefinic concentration above the normal equilibrium concentration tends to oppose the formation of additional benzene and lower olefines by mass action. This tends to suppress the breaking up of alkylated aromatics formed in the earlier stages to form benzene and lower olefines in the later stages of the cracking operation.

55 60 65 Whether the theory above set forth be correct or not, increasing the benzene and lower olefinic concentrations above that produced by the normal formation of benzene and lower olefines from the oil in the cracking operation favors an increase in the yield of alkylated aromatics relative to the yield of benzene.

70 75 The increased concentration of benzene and lower olefine or olefines may be secured by introducing additional benzene and lower olefine or

olefines into the cracking chamber during the cracking of the oil.

In accordance with this invention, all or part of the benzene and lower olefinic material may be separated from the products of cracking and recycled through the cracking chamber or chambers by scrubbing from the gas with the hydrocarbon feed oil benzene and lower olefinic material in a two step operation, removing intermediate hydrocarbons separately. Benzene and lower olefinic material are thus separated from the gas by absorption in the hydrocarbon oil prior to the admission of the oil into the cracking apparatus, as through supply means 21 or 24 in the drawings. However, as temperatures in the cracking apparatus, such as the carburettor and superheater above described, may be widely varied with different cycles and methods of operation, it will be understood that the oil with benzene and lower olefinic material in admixture may be fed to the set at any other appropriate point or points.

The benzene and lower olefinic material recycled in this manner need not be relatively refined, but may be crude cuts washed from the make gas in the manner described. In fact, a very materially increased yield of styrene, a very valuable alkylated aromatic can be secured by washing from the gas with make oil and recycling a light oil cut containing considerable quantities of toluene, xylene, and styrene, in addition to benzene, and a light oil cut containing considerable quantities of butadiene, isobutylene, propylene and even cyclopentadiene and methane, in addition to ethylene.

However, it is preferred to separate from the gas after the initial scrubbing operations for the absorption of benzene and prior to the scrubbing operation for the absorption of lower olefinic material, substantial proportions of all hydrocarbons present of five and four carbon atoms to the molecule.

It is to be understood that additional benzene or lower olefinic material or both over and above that removed from the gas may, if desired, be added to the hydrocarbon oil prior to its admission to the cracking apparatus and/or such additional benzene or lower olefinic material or both may be introduced separately to the same portion or portions of the cracking apparatus or to a different portion or portions.

The invention will be further understood upon reference to Figure 2 of the drawings which comprises a flow sheet illustrating apparatus for carrying out the invention.

In Figure 2, 30 represents a gas set shown diagrammatically as comprising generator 31, carburettor 32, superheater 33 and wash box 34 all connected in series.

Gas off-take 36 from the wash box 34 leads to a condenser 37 which in turn has a gas off-take 38 leading to tar mist extractor 39.

From mist extractor 39 the gas flows through line 40 to relief holder 41 and as shown from relief holder 41 through line 42 through compressor or booster 43 and line 44 to and through purifier system 45 of any suitable design and then through line 46 into scrubber 47. The compressor or booster 43 may be placed either upstream or downstream from purifier system 45. In dry purification for example, it is usually placed downstream.

The purifier system 45, which may be of the dry purification or liquid purification or other type, serves to remove from the gas various im-

purities such as sulfur and cyanogen containing compounds of which hydrogen sulfide and hydrogen cyanide are examples. Since it is preferred not to build up a high concentration of these materials in the set by recycling, the use of a purifier system upstream from the scrubber 47, for example of the type used in ordinary gas manufacture, is recommended.

On the other hand, since condensation of hydrocarbons is undesirable in purifier systems and particularly in those of the oxide type, as a protection against any considerable condensation of higher boiling hydrocarbons in the purifier system, a part or all of the purification may take place downstream of scrubber 47. A second purifier system 45a has been illustrated for this purpose, the use of which is optional.

The apparatus described in Figure 2 up to scrubber 47 and its hook-up may be regarded as illustrative and any other suitable apparatus or system or hook-up might be substituted.

An oil supply for the set 30 is illustrated at 48 from which oil flows as through pump 49 and line 50 to scrubber 47, wherein oil and gas are contacted by any suitable means known in the art for the purpose of scrubbing higher boiling constituents from the gas. Towers whether of the packer or bubble plate variety or otherwise are very suitable for this purpose. Other types of scrubbers will be found in the art.

As pointed out previously, there will be a higher percentage of total benzene present in the gas just prior to entering scrubber 47 than of higher boiling light oil constituents, such as toluene, styrene, xylene, etc., although there may be significant quantities of the latter substances present depending upon the temperature to which the gas has been reduced by the time it reaches scrubber 47.

As an illustration, if the gas is reduced to a temperature of 95° F. prior to entering scrubber 47, it might have present of the order of approximately $\frac{1}{3}$ of the total toluene, 80% of the total benzene, from 10 to 30% of the total xylene, and from 10 to 30% of the total styrene. Reference is made to my copending application Serial No. 301,330, filed October 26, 1939.

These materials are washed from the gas in scrubber 47 to an extent dependent upon (1) the efficiency of contact, and (2) the amount of wash oil employed per unit of gas scrubbed.

When the make-gas is substantially all oil gas with no or very little water gas, the rate of feed oil to the gas set 30 may run as high as 12 to 15 gallons or more of oil per thousand cubic feet of gas. This will, of course, vary with the B. t. u. per cubic foot of the gas, or in other words, with the extent to which the oil is cracked to form gas. For instance, the more the oil is cracked, the larger the volume of gas produced per unit of oil, and vice versa.

Assuming that all of the feed oil is contacted with the gas under fairly efficient contact conditions, and depending somewhat upon the composition of the gas which may vary, this scrubbing step will remove from the gas substantially all of the remaining styrene, xylene and toluene, the preponderate part of the benzene and a part of any hydrocarbons present of 5 carbon atoms, such as cyclopentadiene.

The feed oil thus enriched flows through line 51 to a second scrubber 57 for the removal of lower olefinic material to be more particularly referred to hereinafter.

Should it be desired to reduce the ratio of oil

to gas in scrubber 47, for instance, to reduce the percentage of C₅ hydrocarbons scrubbed out, this might be done by providing a by-pass around scrubber 47 illustrated generally as line 52, which is shown provided with a valve 53.

Accordingly, it will be seen that the feed oil may be charged in scrubber 47 with various amounts of benzene as well as other constituents boiling in the neighborhood thereof.

Should it be desired to recover substantially all or a larger proportion of the xylene, styrene and toluene present in the gas prior to its entering scrubber 47, this may be done by any suitable means, such as by a further reduction in temperature, for example at condenser 37, or by adding an additional condenser, recovering these constituents as condensates.

Other means for regulating the proportion of the various constituents in the gas entering scrubber 47 will become apparent to persons skilled in the art upon becoming familiar herewith.

It will, of course, be understood that scrubber 47 is illustrated diagrammatically and may take any form, shape or construction suitable for the purpose and may comprise one or more units as desired. The same applies to scrubber 57.

While temperature regulating means for scrubber 47 have not been illustrated, it is to be understood that such may be provided, for instance for a control of the absorbing capacity of the oil. Decreased temperature will, of course, increase the absorbing capacity of the oil. Increased pressure might be employed for this purpose with or without decreased temperature.

The scrubbed gas, as illustrated, leaves scrubber 47 through line 54 and passes through a condensate recovery system 55 for the recovery of C₅ and C₄ hydrocarbons from which the residual gas flows off through line 56 to scrubber 57.

The condensate recovery system 55 may be of any suitable design and its purpose is to take out of the gas hydrocarbons of five and four carbon atoms, such as cyclopentadiene, butadiene, isobutylene, etc.

For the purpose of such further condensation prior to the entry of the gas into scrubber 57, or the aforementioned further condensation prior to entry of the gas in scrubber 47, refrigeration, compression, absorption such as in scrubbing oil, adsorption such as on activated carbon, and combinations of the foregoing are available. The construction and operation of suitable systems will occur to persons skilled in the art upon becoming familiar herewith.

In scrubber 57 the gas and hydrocarbon oil are contacted under conditions which increase the absorptive capacity of the oil beyond that obtaining in scrubber 47. This is obviously necessary since lower olefins in any substantial quantity were not removed in scrubber 47.

An increase in the absorptive capacity of the hydrocarbon oil in scrubber 57 may be obtained by increasing the pressure in scrubber 57 such as by booster or compressor 58 and pump 59 in gas line 56 and oil line 51 respectively, or by a reduction in temperature in scrubber 57, or both.

In the event of an increase in pressure in scrubber 57, control valve 60 in charged oil line 62 and valve 61 in residual gas line 63 are conveniently employed.

Although it will usually be desired to bring all of the hydrocarbon feed oil into contact with the gas in scrubber 57, if desired a part of it may be

bypassed such as through bypass 64, shown controlled by a valve 65.

If desired a part of the oil from supply tank 48 may be bypassed to set 38 through lines 68 and 69 or lines 68 and 10 or both as desired.

Means for feeding enriched feed oil to the superheater 33 such as for reverse run purposes is shown at 71.

In order to provide for the continuous flow of hydrocarbon scrubbing oil through scrubbers 47 and 57, as opposed to the intermittent feeding of the charged hydrocarbon oil into the cyclically operated set 38, a surge tank 66 may be provided in line 62.

10 Relief holder 41 provides for the continuous flow of gas through scrubber 47, extraction unit 55 and scrubber 57 as opposed to the intermittent flow of make-gas to relief holder 41 through line 40.

15 It will be understood, however, that scrubber 47, extraction unit 55 and scrubber 57 may be operated continually, intermittently, or otherwise if desired, without departing from the broad concept of the invention.

20 Any desirable pressure or low temperature, or both may be employed in scrubber 57.

25 For example, when employing of the order of from 12 to 15 gallons of scrubbing oil per MCF of gas, pressures of the order of 200 pounds per

30 square inch at atmospheric temperature cause the absorption in the oil of the order of 25% of the propylene and 8% of the ethylene contained in the gas.

35 In view of the relatively large percentages of propylene and ethylene in the gas, the hydrocarbon feed oil is thus charged with substantial quantities thereof.

40 Any desired temperature and pressure in scrubber 57 might be employed through an economic balance between super-atmospheric pressure and sub-atmospheric temperature to obtain the desired absorption of lower olefinic material will usually be sought.

45 The final residual gas leaves scrubber 57 through line 63 controlled by valve 61 and the hydrocarbon oil charged with benzene and lower olefinic material leaves scrubber 57 through line 62 and flows via surge chamber 66 and expansion valve 68 into gas-making set 38, expansion valve 68 being operated intermittently as required in the operation of set 38.

50 It is, of course, understood that, if desired, additional quantities of benzene and lower olefinic material may be charged to the set either via the feed oil or otherwise.

55 Furthermore, while it is desired to have the feed oil flow serially through scrubbers 47 and 57 because of the increased absorptive capacity of the oil in scrubber 57 due to the presence of benzene, the oil stream may be split if desired, and caused

60 to flow in individual streams through the scrubbers, the streams being again united or fed separately to set 38, or otherwise. Other variations may be made without departing from the broad concept of the invention. Thus separate streams of different types of hydrocarbon oil might be employed, one stream flowing through each scrubber and the streams then united or fed separately to the set.

65 Line 63 leads to a storage holder for residual gas or to any other desired point not shown.

70 The residual gas is unusually low in illuminants and from this standpoint may be substituted for natural gas for standby or displacement or other purposes. My process has an added advantage

from this standpoint in that upon analysis of a typical residual gas sample it was found to contain considerably more methane and considerably less hydrogen than residual gas made without added benzene and lower olefines.

The three shell set and cycle earlier described were given merely for convenient illustration of apparatus adapted for use with my invention, and are subject to very wide modification. If a fuel bed is employed for heating the set, as in carburetted water gas practice, it may be preferable to curtail sharply or to omit the production of blue water gas, employing the fuel bed merely as a means of heating the carburetter and super-heater. In such case, in the absence of the blue water gas and excess steam cracking atmosphere, it is desirable to admit steam or other diluent to the carburetter with the hydrocarbon oil to reduce the partial pressures of the vapors and products of cracking. This steam may be admitted through a supply means such as 23. The fuel bed, of course, may be replaced by any other convenient means of heating such as an oil, tar, or gas burner as illustrated at 5 in which case it is also desirable to admit steam or other diluent with the oil. The above modifications are merely illustrative. The invention is applicable to any process in which hydrocarbon oil is thermally cracked under temperature and contact conditions yielding relatively fixed gas and more readily condensable hydrocarbons including benzene, lower olefines and alkylated aromatics.

Referring now to Figure 3 wherein cracking apparatus of the continuous or continual type is illustrated on a laboratory scale, 75 comprises a reaction tube which may be any suitable material such as quartz, or any of the materials at present employed in continuous or continual cracking operations.

Tube 75 at its inlet 76 is shown provided with a baffle 77 in the form of a cup into which project oil feeding tube 78 and steam feeding tube 79. Feeding tubes 78 and 79 pass through and form a gas-tight fit with a closure member 80 for the inlet end of tube 75.

Tube 75 adjacent its outlet end 81 is provided with a gas delivery side arm 82 and a closure member 83, the latter being sufficiently below side arm 82 to form a well 84.

Tube 75 is also shown provided with an axially arranged tube 85 of small diameter. Tube 85, as shown, projects through closure members 80 and 83 and provides a convenient way of arranging thermocouple junctions for the measure of temperature. Tube 85 may be of any convenient material, such as quartz, or any other material suitable for continuous or continual cracking purposes.

Tube 75 may be of any convenient length which is usually correlated with the provisions for feeding steam and for feeding and vaporizing oil in order to make it possible to obtain times of contact within a desired range.

For temperature control purposes, tube 75 is shown surrounded with a heating member 87 in the form of a resistance winding which may be provided with several taps, as illustrated at 88; a cooling coil 89 of tubular construction for the flow of cooling fluid; and another resistance winding 90 provided with suitable taps, illustrated at 91.

It will be seen that the provision of a cooling coil 89 between resistance windings 87 and 90,

and the provision of taps 88 and 91 on windings 87 and 90 respectively, make it possible to closely control temperature conditions within tube 75 as well as to vary such conditions along tube 75, if and as desired.

Assuming that heaters 87 and 90 and cooler 89, if necessary, are operating to establish desired temperature conditions within tube 75, the operation of the apparatus shown in Figure 3 is as follows:

Oil is fed in through tube 78 and steam through tube 79. Both oil and steam strike baffle 77, thus becoming mixed. The resulting reduction in partial pressures of oil vapors and the surrounding temperatures are ordinarily sufficient to vaporize all of the oil.

The vaporized oil in passing through tube 75 is decomposed in a manner similar to that already described in connection with Figure 1.

20 The resin-forming hydrocarbons along with saturated aromatics, such as benzene, toluene, xylene, etc., because of the temperatures involved remain in the vapor phase and pass off through delivery arm 82 with the gas.

25 Temperatures between 1250 and 1550° F. are illustrative of those obtaining in tube 75, although any other desired temperature or temperatures suitable for the purpose may be employed.

20 Times of contact of from 0.5 to 3 seconds are 30 illustrative, although any other desired time of contact suitable for the purpose may be employed.

In substituting the apparatus of Figure 3 in Figure 2 for that of Figure 1, elements 30 to 34 35 are eliminated, delivery arm 82 is connected to gas off-take 36, and line 62 is connected to oil feed tube 78, whereupon elements 36 to 66 are made to function in all respects similar to that already described in connection with Figure 2.

40 The apparatus of Figure 3 is of course largely for illustration and may be replaced by a plant size unit or units. Obviously, any desired heating means may be employed.

45 If desired, tube 75 may contain refractory material of suitable size and shape if sufficient free space is afforded for the flow of vapors, such additional refractory materials providing additional contact surfaces.

50 Small amounts of free carbon or other non-vaporizable substances tend to collect in well 84 from which they may be removed during cleaning upon the removal of closure member 83.

55 When the walls of tube 75 become coated with a layer of carbon sufficiently thick to interfere with proper heat exchange, or otherwise, it may be removed by any suitable means such as by introducing air or oxygen through tube 78 or 79 or both, the products of combustion being removed through side arm 82.

60 Any desired proportion of steam to oil may be employed in my process of which two volumes of steam to one volume of oil vapors is illustrative.

65 As above stated, the yield of styrene, a very valuable alkylated hydrocarbon, may be very materially increased by recycling light oil and hydrocarbons of less than four carbon atoms separated from the gas in the manner described. The feed oil, for example may contain ethylene, propylene, benzene, toluene, a smaller quantity of xylene and still smaller quantities of indene and styrene.

70 As examples of the increased yields of valuable alkylated aromatic hydrocarbons in the labora-

tory apparatus of Figure 3, the following may be given.

EXAMPLE 1

To a mixture of a particular crude oil and benzol in proportions of two parts oil and one part benzol by volume was added 0.905 pound of ethylene per gallon of oil. The mixture of oil, benzol and ethylene was cracked under substantially similar conditions of temperature and contact as a control employing 100% of the same crude oil in a quartz contact tube known commercially as "Vitrosil."

The inside diameter of the tube was 1 1/8" and the length was 35.4".

In each case steam was admitted with the material cracked. The table below shows the increased yields of certain valuable alkylated aromatic hydrocarbons, especially styrene when employing a mixture of oil, benzene and ethylene, the term alkylated being used herein and in the claims to include unsaturated as well as saturated hydrocarbon side chains.

Table I

	Mixture of oil, benzol and ethylene	100% oil
	Lbs./gal. of oil	Lbs./gal. of oil
Styrene.....	0.242	0.079
Toluene.....	0.396	0.289
Methyl styrene+indene.....	0.173	0.111
Net benzene.....	—0.321	0.348

There were also obtained 0.173 pound per gallon of oil of dienes comprising butadiene, cyclopentadiene and dimer, isoprene and piperylene.

EXAMPLE 2

To a mixture of a particular crude oil and benzol in proportions of 2 parts oil to one part benzol by volume was added 1.512 pounds of propylene per gallon of oil. The resulting mixture was cracked under substantially similar conditions of temperature and contact as a control employing 100% of the same crude oil in the tube of Example 1.

In each case steam was admitted with the material cracked. The table below shows the increased yields of certain valuable alkylated aromatic hydrocarbons, especially styrene when employing a mixture of oil, benzol and propylene.

Table II

	Mixture of oil, benzol and propylene	100% oil
	Lbs./gal. of oil	Lbs./gal. of oil
Styrene.....	0.206	0.079
Toluene.....	0.392	0.289
Methyl styrene+indene.....	0.167	0.111
Net benzene.....	—0.505	0.348

There was also obtained 0.252 pound of dienes per gallon of oil comprising butadiene, cyclopentadiene and dimer, piperylene and isoprene.

Other modifications in procedure in the performance of my invention than those set forth above will occur to those skilled in the art upon becoming familiar herewith.

For instance, pyrolysis may be supplemented by other means for decomposing the oil of which catalysis is an example. Thus a combination of temperature and catalyst is within the purview of the invention.

The term hydrocarbon oil as used herein embraces petroleum oil whether in the form of the crude or any liquid fraction thereof suitable for gas-making purposes.

Therefore, changes, omissions, additions, substitutions and/or modifications may be made within the scope of the claims without departing from the spirit of the invention.

I claim.

1. In the manufacture of combustible gas rich in methane and valuable saturated and unsaturated normally liquid aromatic hydrocarbons and valuable unsaturated hydrocarbons of at least 4 and less than 6 carbon atoms per molecule involving the vapor phase pyrolysis of petroleum oil in a heated petroleum oil pyrolyzing environment in the presence of added benzene and in the presence of at least one added olefine having less than 4 carbon atoms per molecule, with the production of gaseous products of pyrolysis containing benzene and saturated and unsaturated hydrocarbons boiling higher and lower than benzene including hydrocarbon material boiling in the neighborhood of the boiling point of benzene,
- 15 said saturated and unsaturated hydrocarbons boiling higher than benzene including saturated and unsaturated aromatic hydrocarbons, said hydrocarbon material boiling lower than benzene including unsaturated hydrocarbons of at least 4 and less than 6 carbon atoms per molecule and including olefines of less than 4 carbon atoms per molecule and methane; the steps of removing from said gaseous products of pyrolysis at least a substantial portion of said hydrocarbon material boiling higher than benzene; thereafter contacting the remaining gaseous products with petroleum oil to absorb therein from said products benzene and hydrocarbon material boiling in the neighborhood of the boiling point of benzene, together with at least the bulk of any remaining hydrocarbon material boiling higher than benzene, leaving in said gaseous products unsaturated hydrocarbon material of at least 4 and less than 6 carbon atoms per molecule together with olefines of less than 4 carbon atoms per molecule and methane; thereafter separately removing from the remaining gaseous products hydrocarbon material of at least 4 and less than 6 carbon atoms per molecule; thereafter contacting the yet remaining gaseous products with petroleum oil to absorb therein from said yet remaining gaseous products at least one olefine of less than 4 carbon atoms per molecule, leaving a residual gas rich in methane; and introducing said petroleum oil containing said absorbed benzene and hydrocarbon material boiling in the neighborhood of the boiling point of benzene, and said absorbed olefine into said petroleum oil pyrolyzing environment for pyrolysis therein.
2. In the manufacture of combustible gas rich in methane as well as valuable saturated and unsaturated normally liquid aromatic hydrocarbons and valuable unsaturated hydrocarbons of at least 4 and less than 6 carbon atoms per molecule by a cyclic process in which heat is stored in a petroleum oil pyrolyzing zone during a heating period of the cycle and in which petroleum oil is pyrolyzed in vapor phase in said heated zone in the presence of added benzene and in the presence of at least one added olefine of less than 4 carbon atoms per molecule during a petroleum oil pyrolyzing period of said cycle, with the production of gaseous products of pyrolysis containing benzene as well as saturated and unsaturated aromatic hydrocarbons boiling higher than benzene

and saturated and unsaturated hydrocarbons boiling lower than benzene, said hydrocarbons boiling higher and lower than benzene including hydrocarbon material boiling in the neighborhood of benzene and said hydrocarbon material boiling lower than benzene including unsaturated hydrocarbons of at least 4 and less than 6 carbon atoms per molecule as well as olefines of less than 4 carbon atoms per molecule and methane; the steps comprising separating from said gaseous products of pyrolysis at least a substantial portion of said aromatic hydrocarbon material boiling higher than benzene; thereafter contacting the remaining gaseous products of pyrolysis with petroleum oil to absorb in said oil from said products benzene and hydrocarbon material boiling in the neighborhood of the boiling point of benzene as well as at least the bulk of any remaining hydrocarbon material boiling higher than benzene while leaving in said gaseous products of pyrolysis 20

5 at, least a considerable portion of said saturated hydrocarbon material of at least 4 and less than 6 carbon atoms per molecule together with olefines of less than 4 carbon atoms per molecule and methane; thereafter separately removing from the then remaining gaseous products of pyrolysis hydrocarbon material of at least 4 and less than 6 carbon atoms per molecule; thereafter contacting the yet remaining gaseous products of pyrolysis with petroleum oil to absorb in said oil from said products at least one olefine of less than 4 carbon atoms per molecule leaving a residual gas rich in methane; and introducing said petroleum oil containing said absorbed benzene and said absorbed hydrocarbon material boiling in the neighborhood of the boiling point of benzene and said absorbed olefine into said petroleum oil pyrolyzing environment for vapor phase pyrolysis.

EDWIN L. HALL.
